Specification of Letters Patent.

Patented Oct. 7, 1913.

Application filed April 6, 1912. Serial No. 688,927.

To all whom it may concern:

Be it known that we, ALFRED PRIOR and RICHARD WILLIAM BRICKELL, both subjects of the King of Great Britain, residing at 5 Dunedin, New Zealand, have invented new and useful Improvements in Boxes, of which the following is a specification.

Our invention relates to wood-rimmed light boxes for containing confectionery and 10 the like, and in particular to the hinging and attaching of the lids thereof.

The object of our invention is to enable the lining and frilling of the box to be done before the operation of fitting on the 15 lid, and to provide a lid that folds freely back and has a neat appearance, these advantageous results being attained moreover at less cost in labor than with the construction hitherto usually followed.

20 Referring to the accompanying drawings—Figure 1 is a perspective view of a box showing the lid attached according to our invention. Fig. 2 is a detail cross section enlarged, illustrating the first step in 25 the hinging of the lid, and Fig. 3 is a similar view showing the hinging completed.

Referring to the accompanying drawings, the box has the usual wooden sides (1) and 30 ends (2) with cardboard or wood bottom (3) and is banded all around with the usual colored paper (4) the edges of which are turned over and in at the top (5) and bottom and at the corners in the usual manner, the bottom being covered if desired by 35 another piece of paper. After this has been done, any frilling or the like can be placed in position around the inside of the box. According to this invention the lid (6) is next prepared for attachment as follows:—

40 A piece of cardboard of the required size is cut out and along the edge to be hinged a strip of linen (7, 8) or other material suitable for the purpose, is glued, so that half (7) of the said strip is attached to one side 45 of the lid, and the other half (8) projects from the edge of the lid. The lid is then laid in position on the box, as shown in Fig. 2, with the projecting part (8) of the linen strip lying along the top edge of the side 50 (1) of the box, and the linen strip is secured along its center or fold to the top edge of the box as shown preferably by means of a suitable number of wire staples (9) driven through the strip into the said top edge by 55 a stapling or other suitable machine. These staples are made to pass approximately

through the center or fold of the linen strip from end to end, adjacent to the edge of the lid to which the strip is glued. When the stapling is completed the free half (8) 60 of the linen strip is turned up on to the side of the lid opposite that to which the first half (7) is glued, into the position shown in Fig. 3, thus completing the hinge which is formed by the staples (9) passing 65 through the center or fold of the linen strip. The linen strip may first be stapled or otherwise fastened along its center or fold to the top edge of the box, and the edges of the 70 strip afterward glued one on each side of the lid respectively so as to attach the lid: or the method hereinbefore described may be followed, but the important feature of our invention is that the stapling must be on the inside of the strip within the fold there- 75 of. Instead of a continuous strip for the hinge the hinge may be in several portions separated from each other, with staples passing through or over the folds of the sep- 80 arate portions into the wood. The lid cov- 85 ering paper (10) is pasted on to the lid and turned in along the outer ends, outer cor- 90 ners, and free side thereof, the colored outer surface of the linen strip finishing off the hinged side. The usual inside label (11) 95 is then pasted on.

Having now described our invention what we claim is;

1. In combination a box lid, a strip of pliable material secured to both surfaces of 90 said lid over an edge thereof forming a fold, and a series of staples having their heads within said fold and their legs passing through said strip substantially as and for the purposes set forth. 95

2. In combination a box lid, a side of a box, a strip of pliable material secured to both surfaces of said lid over an edge thereof forming a fold, and a series of staples within said fold passing through said strip 100 at said fold and entering the upper edge of said side of said box substantially as de- 105 scribed.

3. In combination a box lid, one or more strips of pliable material secured to both 105 surfaces of said lid over an edge thereof forming folds in each strip, and a series of staples with their heads within said folds and their legs passing through said strips substantially as and for the purposes set 110 forth.

4. In combination a box lid, a side of a

box, one or more strips of pliable material secured to both surfaces of said lid over an edge thereof forming folds in each strip and a series of staples with their heads within 5 said folds and entering the upper edge of said side of said box substantially as described.

In testimony whereof we have signed our

names to this specification in the presence of two subscribing witnesses.

ALFRED PRIOR.
RICHARD WILLIAM BRICKELL.
